ABSTRACT OF THE DISCLOSURE

The radio frequency generator of a sputtering system is inductively coupled to a sputter target to achieve radio frequency power transfer and impedance matching between generator and target. The radio frequency generator assembly containing the primary winding of a radio frequency coupling transformer is adjustably positioned over the secondary winding of this transformer, which is disposed in juxtaposition to the vacuum enclosure and to the sputter target contained therein, to achieve sputtering. The inductive coupling allows impedance matching through varied degrees of coupling between the primary and the secondary coils, thus eliminating need for a radio frequency transmission line and associated impedance matching devices between frequency generator and the sputter target. This reduces the total volume required for the radio frequency components; it simplifies the operation; and eliminates the danger of radio frequency radiating from a mismatched cable connection.

The present invention relates to radio frequency sputtering apparatus. In such apparatus an ionizing discharge is employed in a controlled gas atmosphere to bombard a negatively biased material with positively charged gas ions.

The sputtering of dielectrics from a dielectric target cannot be accomplished solely by negatively biasing the target, because a positive surface charge caused by initial ion bombardment collects on the target surface inhibiting further bombardment by positive ions. Therefore, dielectrics can only be sputtered when some means is provided to neutralize the positive charge built up by positive ion bombardment. This has been done heretofore by application of a high-frequency alternating current to the target to be sputtered. Thus, it is possible to neutralize the positive surface charge by electrons attracted to the target during each positive half cycle of the RF wave so that the target may be sputtered again by ion bombardment during the next negative half cycle. Generally RF power dissipated by the target makes it necessary to cool the target and target support, to maintain the target a proper operating temperature. Prior attempts at cooling ion targets have resulted in quite complicated and electrically inefficient structure.

One of the main problems encountered with RF sputtering is efficient coupling of power from the RF power supply to the RF target via fixed impedance transmission lines.

Heretofore, radio frequency generating systems for sputtering dielectrics have included an RF generator, a first impedance matching coupling device, an RF transmission line or cable, a second impedance matching coupling device, and an RF electrode target, capacitively coupled or directly connected to the second coupling device. The impedance of commercially available RF cables does not exceed the relatively low value of 300 ohms while the output impedance of the RF amplifier anode circuit is in the kilo-ohm range. The RF energy has therefore to be transmitted through such a cable to the sputter target where a matching network brings the impedance from the low impedance of the cable back up into the kilo-ohm range

of the sputter target. Any mismatch between the RF amplifier output and the RF cable and/or between the RF cable and the target creates power losses; and even the most carefully designed matching networks have power losses. These losses heat up the cable and make it radiate RF energy just as if it were an antenna, both very undesirable effects. Radio frequency radiation from the RF cable always exists to some degree in practice.

Also the number of components required in the networks is high; and since these components are variable inductors and variable capacitors requiring high voltage ratings, they are expensive and space consuming. Heretofore, the RF amplifier tubes have been cooled by forced air or by convection; but the sputter target was water cooled. Further, the water cooling of the target necessitated elevation of the cooling water from ground potential to the RF target potential and back to ground. This is generally done by conducting the water through two coiled lengths of insulating tubing, which requires space within the shielded box of the matching network to keep the coils from radiating RF frequency.

The primary objects of this invention are to eliminate RF power losses, to increase the overall efficiency, to reduce the number of components in the power supply, and to provide a unit much more compact than known RF sputtering apparatus.

Another object of the invention is to provide a unit of the character described with which the radiation of RF energy is reduced to negligible levels.

Another object of this invention is to eliminate the radiation of radio frequency into space even under conditions of extreme mismatch between the components.

Another object of the invention is to provide a unit of the type described in which low voltage breakdown components may be used.

Another object of this invention is to provide a single structure that functions as a radio frequency coupling device, an ion target support, and a means for conducting a coolant to cool the ion target and ion target support during the presence of radio frequency energy in the structure.

Further objects of the invention are to provide a water cooling system for a unit of the character described in which both water inlet and water outlet may be at ground potential and which lends itself to reduction of the size of the RF generator.

The above and other objects of the invention will be apparent hereinafter from the following description and from the recital of the appended claims particularly when read in conjunction with the accompanying drawings.

Several different embodiments of the invention are illustrated in the accompanying drawings wherein:

FIG. 1 is a diagrammatic view of sputtering apparatus made according to one embodiment of this invention;

FIG. 2 is the schematic diagram of a preferred circuit embodiment of the RF generator, inductive coupling device and RF target electrode;

FIG. 3 is a fragmentary sectional view taken at right angles to the view of FIG. 1 and showing that the RF sputtering apparatus has a coil mounted entirely outside the evacuable enclosure;

FIG. 4 is a diagrammatic view illustrating a further embodiment of the invention;

FIG. 5 is a longitudinal section taken on the line 5—5 of FIG. 6 showing a preferred construction of RF generator;

FIG. 6 is an end view of this generator;

FIG. 7 is a longitudinal section showing a preferred form of target mounting and the means for supplying current to and for cooling the target; and

FIG. 8 is a fragmentary section on the line 8—8 of FIG. 7, looking in the direction of the arrows.

In the apparatus of the present invention the radio frequency power supply is mounted directly on the sputter target feed through an insulator. The final amplifier may be mounted on top of the bell jar. This completely eliminates the need for a power transmission cable, and thereby 5 eliminates losses through impedance mismatch.

The grid and screening power supply are made from conventional components on a separate chassis. This chassis is then mounted on insulators and latched to ground by a capacitor.

The invention is characterized by a sputtering apparatus having a radio frequency generator inductively coupled to RF electrode target inside an evacuable enclosure. The RF electrode target includes a coupling coil mounted on the outside of the enclosure with one end of the coil coupled to the target. The RF electrode target coil is fabricated from a conduit having two passages for conveying a coolant through the coil to and from the target.

Referring now to the drawings by numerals of reference and first to FIG. 1, 10 denotes the evacuable enclosure of a sputtering apparatus. A vacuum pump system 11 is connected to the enclosure 10 through an inlet 12; and a source of gas 14, preferably argon, is connected to the enclosure through a valve and duct 16.

Mounted outside the enclosure is an inductor 20. The inductor 20 comprises two helical coils 21 and 22 wound one upon the other. The coils are wholly outside the enclosure which has an opening 18 in its wall 17, on the inside of which is mounted a ring 35 of a suitable insulating material such as, for instance, a ceramic. The ring insulates the coil from the enclosure 10 and supports the ion target 23 (preferably in the form of a plate of material to be sputtered) in a fixed position. This assembly is the RF electrode target support 24. The ring forms, with the opening 18 in the enclosure wall 17, a recess in which the coils 21 and 22 extend into operative proximity to the target.

Ordinarily it is necessary to cool the target. The inductor 20, including the coils 21 and 22, is therefore fabricated from an electrically-conductive tubular conduit connected to a coolant pumping system 25, which may be the same as the coolant pumping systems for the inductor 30 and primary coil 42 which will be described herein-after.

Directly opposite the first inductor 20 in the embodiment shown is a second inductor 30, similar to first inductor 20, and composed of two helical tubes 31 and 32 wound one upon the other. This inductor 30 is constructed to hold or support the substrate 33 (preferably a plate of material to be coated). The assembly is the RF electrode-substrate support 34.

The substrate support is disposed so that when the target 23 and the substrate 33 are in position, the material, which is sputtered from the target 23, impinges on the substrate 33 to form a coating thereon.

The coils 31 and 32 extend through an opening 39 in the wall 27 of the enclosure 10 and are insulated from the enclosure by the insulator 36, which is ring shaped and surrounds the coils so as to form in effect a recess into which the ends of the coils extend. The substrate support 34 itself seals the enclosure so that inductor 30, like inductor 20, lies wholly outside the enclosure.

The inductor 30 is an adjunct to the structure shown in FIG. 1. It may be omitted if desired. It is supplied for etching from the substrate or for biasing the substrate.

The radio frequency generator assembly 40 includes a primary coil 42 (FIG. 2) for inductively coupling an RF generator 43 to target coil 20 and/or substrate coil 30 (FIG. 1) to transmit radio frequency energy to the inside of said enclosure.

FIG. 2 is a schematic diagram of a preferred circuit embodiment of the RF generator associated with the RF generator assembly 40 mounted on the enclosure 10.

The preferred amplifier design is one in which the 75

anodes of the amplifier tubes 50 (FIG. 2), of which four are shown in FIG. 2, are at DC ground potential with the cathodes at a negative potential with respect to ground, so that the primary coil 42, which is electrically connected to the anodes, is also at DC ground potential. This eliminates the need for electrically insulating the tubing of the coil 42 to prevent inadvertent grounding of the circuit through the coolant connecting tube to the water source and drain.

The preferred RF generator includes a push-pull, Class C amplifier, using amplifying tubes 50 which are preferably tetrodes (type 8072) which receive oscillations of preferably 13.56 megahertz, from the oscillator 52, preferably, a pentode (type 5763). However, in some applications a single tube amplifier may be used. A cathode power supply 54, filament power supply 56, bias power supply 58, screen power supply 60, and the oscillator 52 are preferably located outside the generator assembly so that the assembly may be a small and compact unit.

Resistors 62, 64, 66 and 68, inductors 70, 72, and switch 74 are part of the circuit that couples the amplifier tubes 50 to the oscillator 52, and provides for the selection of different numbers of tubes 50 for different output power levels.

Since the RF generator 40 is variably inductively coupled to the coil 20 of the RF target support 23 or to substrate coil 30, stepless impedance matching is obtained.

The capacitors 29, 75, 76, 77 are in circuit relationship with their respective coils 42, or 20 (30) to tune the circuits to their resonant frequency.

To cool the anodes of the RF amplifier tubes 50, the tubes 50 are sealed with O-rings into metal blocks 80, which permit the passage of a coolant, for example, water. In the preferred arrangement, both the anodes of tubes 50 and the coil 42 are cooled by a coolant which enters the coil 42 to 82, flows through the coil 42 into the blocks 80 in conduits 84 and 86, out of the blocks 80 through conduits 87 and 88, through the coil 42 again and out through the conduit at 89. The copper tubes 84, 88, 86, and 87, which form the anode end of the coil 42, connect at the water inlet and water outlet to the metal blocks 80 which have cavities machined in them to provide smooth flow of water over the exterior of the amplifier tubes 50. Conduits 82 and 89 may be connected to a pump or to a cooling water supply.

Similarly, the RF electrode-target support 24 and the RF electrode-substrate support 34 are cooled.

The type of amplifier preferred is a push-pull Class C amplifier using four tubes of the type 8072 in parallel and driven directly by a crystal controlled oscillator having one tube, type 5763. Two considerations led to the use of parallel tubes in the final amplifier. First, six tubes of type 8072, connected as two pairs of three tubes in parallel with their associated components, is considerably more economical than a single pair of larger tubes capable of the same output. Secondly, parallel tube operation permits the selection of any desired number of tubes in parallel to vary the output power of RF amplifier without affecting the output voltage or making it necessary to change the turns ratio of the coupling transformer or other impedance matching means to adapt the power supply to a different size target. The selection of different numbers of tubes in parallel is accomplished by heating only the filaments of the tubes required for the desired output power level. The desired number of tube filaments may be selected by a switch which also selects the values of the screen and grid resistors to maintain proper grid and screen currents for any tubes in operation. The same switch may also be used to change the sensitivity of an overload relay for the anode power supply. This relay senses the anode current and deenergizes the anode power supply in case of an overload. This makes the overload current, which would turn off the anode power, a function of the number of tubes in operation at that time.

Since inductive coupling is employed, a push-pull type amplifier is practical. This has the additional advantage that no even harmonics are generated and that push-pull amplifiers work at a higher level of efficiency. Inductive coupling then allows stepless impedance matching within a certain range by varying the inductive coupling between the RF amplifier tank coil 42 and the coupling coil 20 of the sputter target. To facilitate such variable coupling, the complete RF amplifier box 43 (FIG. 2) may be mounted on a track allowing it to slide over the target coupling coil 20. In FIG. 1, the radio frequency generator 40 is movably mounted by means of rollers 90 and tracks 92 on enclosure 10 so that the coils of the RF generator may be coupled to the coil 20 to transmit RF energy to the target 23.

In operation, after the enclosure 10 is evacuated by pump 11, a small amount of argon gas from source 14 is allowed to enter the enclosure 10. The argon gas is then ionized by application of radio frequency energy transmitted to the target 23 inside the enclosure. This draws positive ions to the target 23 during each negative half cycle of the RF wave, causing ions to impinge upon the target 23 and sputter material onto the substrate 33. During the sputtering process the coolant pumping system circulates coolant through the coil 20 to cool the target. Similarly, the substrate 33 may also be cooled by circulation of water through coil 30.

To transmit radio frequency energy to the target surface 23 so that it may sputter material on the substrate 33, the target holder is inductively coupled to the radio frequency generator 40. Adjustment of the radio frequency generator 40 relative to the enclosure 10 allows variation in the inductive coupling of the radio frequency generator to the target. This variable inductive coupling eliminates the need for an impedance matching network to obtain maximum transfer of RF energy to the target 23.

The coil 30 permits sputtering the surface of the substrate when desired, for example, when cleaning the surface of the substrate and/or preparing the substrate surface so that the coating bonds better.

The embodiment of the invention illustrated in FIG. 4 discloses how both the target and a single tube amplifier can be cooled using a single pair of helically wound coils. Here the target is indicated schematically at 23'. 50' is the amplifier tube. The copper cooling coil is denoted at 100. The water enters this coil at 101, and the coil is helically wound on itself, and delivers the cooling water into the block 80' which is machined with a cavity to provide smooth flow of water over the anode of the amplifier tube 50'. The water flows out of the block 80' to the tube 102 which is helically wound on the tube 100, and which is coiled on itself as denoted at 103 and goes to the back of the target support, and then is coiled on itself again and flows out of the tube at 104.

The cathode power supply of the tube is denoted at 54', the filament power supply at 56', the grid bias power supply at 58', and the screen power supply at 60'. The oscillator or RF drive is denoted at 52'. The connections between the various components may be similar to those disclosed in FIG. 2. The various elements of the tetrode 50' are connected to capacitors 105 which in turn are connected to ground. The inductor 72' forms part of the circuit that couples the oscillator 52' to the amplifier tube 50'. The variable capacitors 75' and 77' permit tuning the circuit.

In this embodiment of the invention, as in the previously described embodiment, all operating power supplies for the radio frequency generator are located in a control cabinet away from the radio frequency generator; the target is inductively coupled to the radio frequency amplifier; the coupling coil consists of the two copper tubes which are electrically connected in parallel to form a twin tube, of which one, 100, serves as the water supply and the other, 102, as the water drain for the target and tube cooling water. Both the water supply

and drain connections are at the RF grounded end of the double coil and are connected to ground through a large capacitor 105. This eliminates the need for having coiled up insulating tubing for the cooling water supply and drain inside the shielding enclosure.

The amplifier tube anode operates at DC ground potential, and the cathode is connected to a corresponding negative potential with respect to ground. Again, this permits connecting the radio frequency grounded end of the tank coil or anode resonance coil of the radio frequency amplifier directly to DC ground. The grounded end of the resonance coil is soldered directly against the wall of the shielding case of the radio frequency amplifier for the purpose of cooling the whole amplifier enclosure.

With a single ended amplifier nearly half of all components required for a push-pull amplifier can be eliminated and an even better shielded coupling junction between the RF power supply and target can be provided. It is also possible to reduce the size of the RF power supply.

In FIGS. 5 and 6, a presently preferred RF amplifier tube mounting and generator is shown. Here the amplifier tube is denoted at 110. The tube is mounted in a housing 116 by means of a gasket 112 and a nut 114, which threads onto the tube. Housing 116 is secured to a slotted cylinder 117 that forms one electrode of the tank circuit capacitor. The other electrode of this capacitor is formed by the outer shield can or housing 118. The coil 120 of the tank or anode resonant circuit is mounted inside the slotted cylinder.

The slot 119 (FIG. 6) in this cylinder has a double function. One is to prevent it from becoming a short circuit winding around the tank coil and the other is to provide spacing between this capacitor electrode and the cooling coil tubing 120 which runs up along the inside of the outer shielding can 118.

The final RF amplifier tube is mounted inside of a screen piston whose wall is denoted at 122. This piston allows the whole inner assembly to slide up and down inside the outer shield can 118. It is insulated from this can by the insulating sheet 123. This sheet, which is made of Teflon, provides both insulation for the screen potential and smooth travel for the piston inside the shield case 118.

The top cover 124 for the housing 118 is press-fit into this housing; and a nut 126 in the center of this cover, which threads on the tuning stud 128, serves as a means for adjusting the frequency of the inner resonant circuit. The plate 136, juxtaposed to the cover 124, is spring-loaded against the cover 124 by the tuning spring 132. The spring strap 134 serves to ground the connector mounting plate 136 to the flange 130 of cover 124. The connector itself between the plate 136 and the cover 124 is denoted at 138.

Further chokes 140 are provided for all cables interconnecting the final RF power supply with its auxiliary power supply for screen grid and filament. The grid drive coil of this tube is denoted at 142. It is wound on the coil spacer sleeve 144 which slides on the stud 146. The grid drive capacitor is denoted at 148. The manifold, through which the cooling water is admitted, and out of which it drains, is denoted at 150. The anode resonant coil 120 is mounted by means of the flange 152 on the housing 116 for the amplifier tube.

A screen piston is provided which comprises disc 133 and wall 122. The whole assembly 122, 133, 136 125, 146, etc. slides on the insulating sleeve 123 inside the can 118. Since one end of the tank coil is connected to the outer shield can 118 and the other end is connected to the anode of the final RF amplifier tube mounted on the inner assembly, the sliding movement effected by the screen piston extends or contracts the length of the anode resonant coil 120 and thereby tunes the frequency of the anode resonant circuit.

FIGS. 7 and 8 in conjunction with FIG. 4 show the presently preferred structure of the evacuable enclosure and of the elements contained therein.

17 again denotes one wall of the enclosure; and 160 is the target plate. The target is secured by screws or dowels 162 to a ceramic insulating ring 164. A "Teflon" insulator ring 166 surrounds ring 164 and is fastened in any suitable manner to the target plate 160 and wall 17. The insulator ring 164 itself is fastened to a clamp plate 168 by adjusting screws 170 and clamp plate 168, in turn, is secured by screws 172 to the can 40.

A variable capacitor 77' is secured by screws 174 to a plate 176, which, in turn, is fastened by screws 178 to target plate 160. The tubular coil 103 is brazed or otherwise secured to the plate 176 and wound about capacitor 77'. Capacitor 105 is connected by strap 180 and screw 182 to the flange 184 of capacitor 77'. A shaft 186, which passes through one wall of can 40', serves as a feed shaft for the capacitor 77'.

There is a ring 190 fastened in the open end of can 40'. This ring acts as a guide for the can 118 which telescopes into it and which is adjustably supported beneath the lower end of ring 190 by studs 197, which thread into the flange 198 of the can and project upwardly for adjustment by knurled nuts 195 whose hubs seat against the lower face of the flange 196 of ring 190. Adjustment of the can 118 in ring 190 effects impedance matching between the coil of the RF generator and the target; whereas the adjustment of the screen piston 122 (FIG. 5) in the can 118 effects tuning.

One of the advantages of the DC grounded anode design for the final radio frequency amplifier is that no DC is superimposed on the radio frequency potentials applied to the components in the anode circuit. This prevents destructive DC arc-over from occurring following a possible radio frequency arc-over. For this reason, the voltage rating of these components is lower, and they are therefore smaller. Also the unplugged unit only exposes grounded components making it very safe to handle.

In comparing this radio frequency power supply design with conventional radio frequency power supplies used for sputtering, it was found that a volume reduction of approximately 1 to 5 was achieved.

When an all-metal vacuum chamber is used for sputtering with this radio frequency amplifier, it is nearly impossible to detect any radiated radio frequency energy.

Additional advantages of the DC grounding of the anode of the final RF amplifier are, as stated, that the inlet and outlet for the target and the RF amplifier anode cooling water are located at the grounded end of a double helical coil which comprises the RF transformer. Loops at the anode and target terminals feed the cooling water to the final RF amplifier anode and to the sputter target. No DC potential is present on the compound of the RF output resonant circuit. This decreases the insulation requirements of all components and makes it possible to mount one side of all components to ground. The danger of DC arcs developing after RF does not exist. Water cooling of the final RF amplifier anode increases the power handling capability of a smaller tube, making a very compact design possible. Furthermore, RF power transmission losses are eliminated. This, in itself, allows use of a smaller unit.

No RF matching network and no transmission line is needed. This alone saves approximately 30% of the total required space. The majority of component failures is known to have occurred in these two components in older RF units. It is estimated that approximately 70% of all repair cost and maintenance on the RF power supply can be eliminated with the present design. RF radiation to the outside is completely avoided since there is no more mismatched cable between units.

The final amplifier tube is water cooled which increases its power handling capabilities, allowing the use of a low price and readily available tube type.

While the invention has been described in connection with certain specific embodiments, thereof, it will be understood that it is capable of further modification, and that this application is intended to cover any modifications or embodiments of the invention coming within the present disclosure and the recital of the appended claims.

Having thus described my invention, what I claim is:

1. Sputtering apparatus comprising an evacuable enclosure, a target support in said enclosure for holding a target of material to be sputtered by ion bombardment, an induction coil mounted outside but on said enclosure and having a helical winding connected to said target support and constituting the secondary winding of a radio frequency coupling transformer, whereby upon operation of said transformer radio frequency energy is transmitted by said coil into said enclosure,
2. Sputtering apparatus as claimed in claim 1, having means mounted externally of said enclosure and operable to develop a radio frequency signal in said primary coil to effect operation of said transformer.
3. Sputtering apparatus as claimed in claim 2, wherein in each of said coils comprises a plurality of convolutions, and means is provided for adjusting the convolutions of said primary coil toward and away from one another to effect tuning.
4. Sputtering apparatus as claimed in claim 1, wherein at least one of said coils is electrically conductive tubing for conveying a coolant.
5. Sputtering apparatus as claimed in claim 4, wherein said secondary coil is electrically conductive tubing for conveying a coolant to cool said target support.
6. Sputtering apparatus as claimed in claim 1, wherein both of said coils are electrically conductive tubing for conveying coolant.
7. Sputtering apparatus comprising an evacuable enclosure having an opening in one wall thereof, an insulating member surrounding said opening and forming therewith a recess in said wall and constituting means for supporting a target in said enclosure, means for generating a radio frequency signal, including a radio frequency coupling transformer comprising a primary helical winding and a secondary helical winding, said secondary winding being disposed in said recess inside said target support but outside said enclosure, and said primary winding being also disposed outside said enclosure but being inductively coupled to said secondary winding.
8. Sputtering apparatus as claimed in claim 7, wherein a housing is mounted slidably on said enclosure, and said primary winding is disposed in said housing, and having means for slidably adjusting said housing relative to said enclosure to match the impedances of said signal generating means and said enclosure.
9. Sputtering apparatus as claimed in claim 8, wherein said primary winding has a plurality of convolutions and means is provided in said housing to adjust the spacing of successive convolutions of said primary winding to tune the radio frequency.
10. Sputtering apparatus as claimed in claim 7, wherein said windings are electrically conducting tubular helical coils for conveying coolant.

11. Sputtering apparatus comprising
an evacuable enclosure,
a target support in said enclosure,
a housing,
a radio frequency generator and a primary transformer
coil coupled thereto and mounted in said housing,
the secondary coil of said transformer being mounted
outside said enclosure and inductively coupled to
said primary coil, and being operatively connected
to said target support to transmit RF signals into
said enclosure upon operation of said generator,
means for varying said inductive coupling,
said secondary coil comprising a double winding of
helical electrically-conductive tubing,
an inlet for supplying a coolant to one of said windings
to cool said support, and
an outlet for draining the coolant from the other of
said windings,
both said inlet and said outlet being at ground
potential. 15
12. Sputtering apparatus comprising
an evacuable enclosure,
a target support in said enclosure,
a housing,
a radio frequency generator and a primary transformer
coil coupled thereto and mounted in said housing,
the secondary coil of said transformer being mounted
outside said enclosure but in operative relation to
said enclosure and inductively coupled to said
primary coil to impart RF energy to said enclosure
upon operation of said generator,
said primary coil comprising a double winding of
helical electrically-conductive tubing,
one of said windings being formed with an inlet
through which a coolant may be supplied to said
tubing, and
the other of said windings being formed with an outlet
through which a coolant may be drained from
said tubing,
both said inlet and said outlet being at ground
potential. 35
13. Sputtering apparatus as claimed in claim 12,
wherein amplifying means including an electronic tube
is mounted in said housing to operatively connect said
generator and said primary coil, and
the mounting for said tube includes a block in which
the anode end of said tube is mounted,
said block has a passage therethrough for coolant,
and said windings are connected to said passage to
deliver coolant into and exhaust coolant from said
block. 50
14. Sputtering apparatus comprising
an evacuable enclosure,
a target support in said enclosure,
radio frequency signal generating means,
a transformer comprising a primary winding and a
secondary winding,
said secondary winding being mounted outside said en-
closure but in operative relation thereto to transmit
radio frequency energy into said enclosure upon
operation of said generating means,
said windings each being electrically conductive and
each comprising a double wound helical electrically-
conductive tube,
the two tubes of the primary and secondary windings
being integral,
one end of the secondary winding constituting an inlet
for coolant, and
one end of the primary winding constituting an outlet
for draining coolant from both windings. 65
15. Sputtering apparatus as claimed in claim 14, where-
in the windings are grounded at inlet and outlet.
16. Sputtering apparatus as claimed in claim 14, where- 75

- in means is provided for varying the inductive coupling
between the two windings.
17. Sputtering apparatus comprising
an evacuable enclosure,
a target support in said enclosure,
a first inductor mounted outside said enclosure but in
operative relation to said target support,
a substrate support in said enclosure,
a second inductor mounted outside said enclosure but
in operative relation to said substrate support,
a source of RF signals for said inductors including a
primary transformer coil, and
means for inductively variably coupling said primary
coil to said first inductor to transmit said RF signals
via said first inductor to said enclosure.
18. Sputtering apparatus as claimed in claim 17, where-
in both said inductors are electrically conductive tubes for
conveying coolant to said target support and said sub-
strate support, respectively.
19. Sputtering apparatus comprising
an evacuable enclosure,
a target support in said enclosure,
a radio frequency generator mounted outside said en-
closure,
a second enclosure mounted on the first-named
enclosure,
said generator having an electronic amplifier tube,
a primary transformer coil mounted in said second en-
closure and electrically connected to said tube,
a block in said second enclosure in which at least the
anode of said tube is mounted,
an electrically conductive secondary transformer coil
electrically coupled to said primary coil and disposed
outside said first-named enclosure but connected
thereto,
said coils being electrically-conductive tubing for con-
veying coolant, and
said primary coil being connected at one end to a
cavity in said block to supply coolant thereto, and
said secondary coil being connected at one end to
said cavity to drain coolant therefrom,
said cavity permitting smooth flow of the coolant over
the amplifier tube mounted in the block.
20. Sputtering apparatus as claimed in claim 19,
wherein said primary coil comprises a double helix com-
posed of one tubular conduit for conducting coolant to
said block and a second tubular conduit for conducting
coolant from said block, said conduits being helically
wound about one another.
21. Sputtering apparatus comprising
an evacuable enclosure,
a target support mounted in said enclosure,
a second enclosure,
a block mounted in said second enclosure,
a radio frequency generator mounted outside of said
second enclosure,
electronic amplifying mechanism mounted in said
second enclosure and connected to said generator,
and including an electronic amplifier tube mounted
on said block to extend into a cavity in said block,
means for cooling said amplifier tube and said target
support comprising first and second electronically
conductive conduits, one of said conduits being con-
nected at one end to a coolant supply and at its
opposite end to said cavity to supply coolant to said
cavity, and being wound between its ends into a
primary transformer coil electrically connected to
said amplifier tube, and the other of said conduits
being connected at one end to said cavity to drain
coolant from said cavity and being wound into a
secondary transformer coil electrically coupled to
said primary transformer coil and then extending
into juxtaposition to said evacuable enclosure and
operatively connected thereto and then being inter- 70

11

wound helically with said secondary transformer coil, and having a discharge port at its end.

22. Sputtering apparatus as claimed in claim 21, wherein both the supply end of said first conduit and the discharge end of said second conduit are grounded. 5

23. A radio-frequency amplifier assembly, comprising a housing for an amplifier tube having at least an anode, a cathode, and a grid, an anode resonant coil mounted on said housing, a longitudinally slotted electrically conductive cylinder 10 surrounding said coil but spaced radially therefrom, an electrically-conductive shield spaced from and surrounding said cylinder, said cylinder constituting one electrode of a capacitor for said amplifier tube, and said shield forming the other electrode of said capacitor, a coolant manifold secured to said shield and connected to a coolant supply and to a coolant drainage tube, said coil being an electrically conductive conduit for 20 conveying coolant and having both its ends extending through said slot to said manifold for sup-

12

ply and discharge of the coolant between said coil and said manifold, and means for adjusting the tube support axially relative to said coil to expand or contract the length of said coil to adjust the frequency of the signal developed by said coil.
